UNITED STATES PATENT OFFICE.

EMIL WAGNER, OF CINCINNATI, OHIO.

WINDOW.

Application filed July 27, 1926. Serial No. 125,292.

This invention relates to improvements in a window frame and has for an object the production of a window frame wherein the lower window sash may be conveniently positioned so that the glass pane may be cleaned from the interior of the room.

Another object of my invention is to provide a window frame wherein the lower reciprocating sash may be positioned so that the outer surface of the glass carried by the sash may be cleansed from the interior of the room.

Another object of my invention is to provide a simple and efficient means whereby the present window frames may be converted into a sash of my improved type.

Another object of my invention is to provide a window frame to accomplish the above objects, wherein the lower sash may be pivoted at the lower end of the frame and comprise means for retaining the sash in its adjusted position.

These and other objects are attained by the means described herein and disclosed in the accompanying drawings, in which:

Fig. 1 is an elevational view of a window frame embodying my invention.

Fig. 2 is an enlarged sectional view taken on line 2—2 of Fig. 1.

Fig. 3 is a fragmental perspective view of the lower portion of the frame shown in Fig. 1 showing the sash in an adjusted position.

Fig. 4 is an enlarged fragmental cross sectional view taken on line 4—4 of Fig. 1 and showing in dotted lines the lower sash in its operative position.

My invention is applicable to an ordinary window frame having a sill 10 and sides 11 and 12 and a top 13. The sides 11 and 12 each carry spaced strips 14 and 15 between which are grooves 16 in which the sides 17 and 18 of the upper sash 19 slide. A strip or molding 20 provides a second groove 21 in which the sides 22 and 23 of lower sash 24 slide. The usual window ropes 25 supported on pulleys 26 and counterbalanced by sash weights 27 are employed in the usual manner and for the usual purposes. The ropes 25 for the lower sash are secured to the sides 22 and 23 of sash 24 intermediate the ends thereof and normally extend through grooved or cut away portions 28 extending upwardly of the securing points 29. The window thus far described operates in

the same manner as the ordinary window 55 having counterweighted sashes.

In adapting my invention to a window such as has just been described, the bead or molding strips 20 are severed a little above the top of lower sash 20. The bottoms of the lower sections of said molding strips are pivoted on pins 30 so that they may be swung downwardly into the room. At their tops these strips carry transversely extending thumb screws 31 which enter threaded holes in countersunk plates 32 for retaining said lower strips in normal position. The upper portions of beads or molding strip 20 are rigidly secured and carry at their lower ends small antifriction rollers 33. The lower bead strips 20 each carry a plate 34 having a tubular portion 35 (see Fig. 2) into which offset pins 36 carried by the lower sash 24 enter when said sash is lowered. The center strips 15 are notched at 37 to provide a clearance for the lower outer edge 38 of lower sash 24 when the said sash is actuated about its pivot 30. Instead of enlarging the center strips 15, to provide this clearance, the opposite ends of the lower outer edge 38 of the sash 24 may be rounded off or removed.

The lower bead or molding strips 20 are secured in spaced relation by a cross or tie strip 39, thereby preventing the inadvertent 85 displacement of either one of the strips. Suitable hooklike members 40 may be secured to the lower sash 24 and receive the tie strip or bar 39, and in conjunction with the offset pins 36 and plates 34 retain the 90 sash 24 and beads 20 in slidable contact. The way 41 formed in the hook members 40 may be used to hold a curtain rod or the like from which a curtain is usually draped or hung.

The operation of the device is as follows: To clean the outer surface of the glass in the lower sash 24, said sash is moved down to a normal closed position so that pins 36 enter tubes 35 on plates 34 and the tie rod 39 is received by the hooklike member 40, thereby securing lower molding strip 20 to sides 22 and 23 of the sash. Thumb screws 31 are then withdrawn from the plates 32. The lower sash may now be tilted inwardly 100 from the top, the lower outer edge 38 entering notches 37 which permit such tilting. The sash ropes 25 pass about pulleys 33 and

support the sash and strips 20 secured thereto, in an inclined position as shown in Fig. 3. The sash weights counterbalance the lower sash in its inclined position as well as in 5 its vertical sliding position. By simply pushing the sash back to its normal position and tightening the two thumb screws 31, the window is again placed in condition for ordinary use.

10 While I have shown but one sash adapted for tiltable movement for cleaning purposes and the like, it will readily be seen that similar movement may also be provided for in the upper sash by using means substantially similar to those shown.

It should be noted that whilst I have disclosed a tie or cross bar 39 and hooks 40 in conjunction with the offset pins 36 and plates 34, for securing the window sash to 20 the molding strip, either one or the other may be eliminated without destroying the efficient operation of my device.

It should also be noted that during rainy weather the lower sash 24 may be tilted as 25 shown in dotted lines in Fig. 4 to provide ventilation in the room and at the same time prevent any rain or the like from entering.

What I claim is:

1. In a window structure the combination 30 of opposed side members having opposed grooves formed therein, each of the grooves being provided with a forward wall pivotally mounted at its one end, a tie rod spaceably securing the walls together at their free 35 ends, a sash reciprocable in the grooves, and means carried by the sash cooperating with the tie rod to lock the sash and forward walls

together to permit unitary movement of sash and forward walls about the pivotal mounting of the forward walls. 40

2. In a window structure the combination of a frame having side walls, the side walls being provided with opposed grooves, a divided molding strip forming the forward wall of each groove, the lower portion of the molding strips being pivoted at their lower ends, a tie rod having its opposite ends secured to the molding strips for retaining the molding strips in spaced relation, a sash reciprocable in the grooves, and hook-like 45 members carried by the sash co-operating with the tie rod to secure the sash to the molding strips so that the sash and molding strips may be actuated as a unit about the pivotal mounting of the molding strips. 50

3. In a window structure the combination of a frame having a pair of side walls, the side walls having opposed grooves formed therein, a window sash reciprocable through the grooves, the forward walls of the grooves 60 being pivoted at their lower ends, a tie rod having its opposite ends secured to the forward walls of the grooves to retain the said forward walls in spaced relation, and means carried by the sash co-operating with the rod 65 for securing the sash to the rod whereby the sash, tie rod and forward walls of the grooves may move as a unit about the pivotal mounting of the forward walls. 70

In testimony whereof, I have hereunto 75 subscribed my name this 24 day of July, 1926.

EMIL WAGNER.
